UNITED STATES PATENT OFFICE.

GARDNER T. EAMES, OF CHICAGO, ILLINOIS, ASSIGNOR TO FANNIE V.
EAMES, OF SAME PLACE.

PULLEY.

SPECIFICATION forming part of Letters Patent No. 375,415, dated December 27, 1887.

Application filed August 22, 1887. Serial No. 247,545. (No model.)

To all whom it may concern:

Be it known that I, GARDNER T. EAMES, of the city of Chicago, in the county of Cook and State of Illinois, have invented certain new and useful Improvements in Pulleys, of which the following is a specification, reference being had to the accompanying drawings, and to the letters of reference marked thereon.

In the accompanying drawings, Figure 1 is a side view of a pulley embodying my invention, certain parts being in section. Fig. 2 is a vertical section on line x x , Fig. 1. Fig. 3 shows details, hereinafter described.

Similar letters of reference indicate similar parts in the respective figures.

A is the rim of the pulley, made of wood, and in sections, as shown, and having an inner web or flange, a , the sections being secured together in a suitable manner.

The spider or central part of the wheel consists of two T-shaped pieces of cast-iron, having each a solid arm, C, and two half or divided arms, C', the center of each half-arm being V-shaped, as shown, the two centers D forming the hub. The entire spider is formed by uniting two such castings, as shown in Fig. 1, the union being effected by bolts c , which pass through the half or divided arms C', as shown. The central opening of the spider when the two castings are brought together is square, as shown in Fig. 1.

The shaft is shown by B, and between the shaft and the centers D of the spider are placed two V-shaped bushings, a' , of cast-iron or other suitable metal. The bushings are shown in perspective in Fig. 3.

It will be seen that the bushings have four bearing-points upon the shaft, by which the shaft is firmly gripped and the pulley kept from slipping.

Each solid arm C is provided with a foot or flange, c' , which fits up against the web or flange a of the rim A, and on the opposite side is a washer, b . By means of the feet or flanges c' , the washers b , and ordinary bolts the rim and solid arms C are securely attached together. A similar attachment is made to the half or divided arms C', except that the feet are divided, as also are the washers shown by b' .

The construction described allows the rim to be readily clamped and secured by the washers on shrinkage occurring, the rim being always kept tight to the spider.

It will be seen that my invention produces an effective, simple, and cheap pulley, and one which can be readily tightened up on shrinkage of the web taking place. The pulley is also strong, light, and easily put together and adjusted.

Having described my invention, I claim—

The rim A, having the inner web or flange, a , and the T-shaped spider-castings having V-shaped centers, combined with the washers b , the V-shaped bushings, and securing-bolts, substantially as set forth.

In testimony whereof I have hereunto set my hand and seal.

GARDNER T. EAMES. [L. S.]
